(57) **ABSTRACT**

Disclosed is an electronic module designed to use the locomotive engine's speed sensors to detect such changes in engine speed (rpm), as required by the locomotive operator moving the throttle notch handle. Once a speed change is detected, the module commands an air valve on each of the locomotive's main air reservoir tanks, (designed to handle the normal operating main reservoir air pressure), to open and allow them to discharge into the engine's intake manifolds located on both sides of the diesel engine.

1**AIR PRESSURE BOOST ASSIST****CROSS-REFERENCE TO RELATED APPLICATION**

This application claims priority to U.S. Provisional Patent Application Ser. No. 60/786,803 filed Mar. 28, 2006, the contents of which are hereby incorporated in their entirety.

ABSTRACT

The present invention provides an intake manifold air pressure boost using a locomotive's main reservoir air supply during diesel engine speed and load transition periods during throttle notch changes.

BACKGROUND

GE locomotive diesel engines are susceptible to short period bursts of high visible smoke levels during throttle notch changes, (speed and load fluctuations).

During these throttle notch changes, the loading demands on the engine are such that the combustion fuel/air ratio is extremely rich, thus creating the situation where the fuel is inefficiently burned resulting in high levels of visible smoke from the locomotive's exhaust muffler or stack.

DRAWING

FIG. 1 is a block flow diagram of the present method and apparatus for detecting a speed change and signaling an air valve to discharge air into an engine's intake manifold.

DESCRIPTION

In order to offset the condition described above, the locomotive's main reservoir air supply is used to increase the

2

intake manifold air supply and pressure to the engine's individual cylinders to help re-balance the combustion fuel/air ratio, thus reducing the smoke levels.

The invention includes an electronic module designed to 5 use the locomotive engine's speed sensors to detect such changes in engine speed (rpm), as required by the locomotive operator moving the throttle notch handle. Once a speed change is detected, the module commands an air valve on each of the locomotive's main air reservoir tanks, (designed 10 to handle the normal operating main reservoir air pressure), to open and allow them to discharge into the engine's intake manifolds located on both sides of the diesel engine.

The additional air pressure boost from the main reservoir tanks is needed for only a short amount of time, which will be 15 confirmed during testing. Once the testing is completed, the electronic control module would then be programmed to open and close the air supply valve as needed.

Some conditions may require different time spans of 20 increased boost due to the extent and level of the unacceptable smoke levels. Therefore, the module must be programmed to determine when these conditions will occur, based on the engine's speed or on the locomotive's trainline throttle position.

What is claimed is:

25 1. A method of reducing emissions for a locomotive comprising the steps of:
 detecting a speed change of the locomotive, wherein the speed change corresponds to a change in a fixed throttle notch position of the locomotive;
 30 signaling an air valve; and
 discharging air from the locomotive's main reservoir air supply into an engine's intake manifold to reduce emissions.
